UNITED STATES PATENT OFFICE.

ANDREW WHELDON BILES, OF GLASGOW, SCOTLAND, ASSIGNOR TO HENRY LEES AND COMPANY, LIMITED, OF GLASGOW, SCOTLAND.

TIPPING APPARATUS FOR WAGONS AND THE LIKE.

Application filed October 31, 1927, Serial No. 230,029, and in Great Britain November 9, 1926.

This invention refers to tipping apparatus for wagons and the like, hereinafter referred to generally as wagons, particularly for effecting discharge from a first position to a second position, which may be close together, involving raising the load. For example, for effecting discharge over a wall from one side to the other.

Apparatus according to this invention 10 comprises a platform for the wagon, a base for the platform to stand on, a main frame on which the platform is mounted to rock, a main axis about which the main frame is mounted to turn, a carrier mounted to turn 15 at or about the main axis, a side rest on the main frame for the outer side of the wagon, a holder on the carrier located above the main axis for the top of the wagon, a weight pivoted to the main frame, a link 20 pivoted to the weight and pivoted to the carrier, the weight and the link and the pivoting being such that in the process of tipping the weight acts upon the carrier and maintains the holder, which is on the carrier, against the top of the wagon.

Examples of apparatus according to this invention will now be described with reference to the accompanying drawings, in which:—

30 Figure 1 is an elevation of an apparatus showing a first position in the process of tipping, and Figures 2 and 3 are similar elevations, Figure 3 showing a second position, and Figure 2 a position intermediate between the first and second.

Figure 4 is an elevation, partly broken away, of the apparatus in a first position and Figures 5 and 6 are similar elevations or diagrams, Figure 6 showing a second position and Figure 5 a position intermediate between the first and second.

Figures 1, 2 and 3 show:—Main frame A. Main axis 2. Platform B pivoted to A at 3. Base C for platform B to stand on. 45 Side rest D on frame A. Carrier E. Holder F on carrier E. Weight G pivoted to main frame A at 4. Link H pivoted to weight G at 5 and to carrier E at 6.

In this example, with the parts in the first position, Figure 1, the pivot 4 is above the main axis 2, and the link H is pivoted to weight G below the pivot 4 and to carrier E below the main axis 2.

Figures 4, 5 and 6 show:—Main frame A. 55 Main axis 2. Platform B pivoted to A at 3.

Base C for platform B to stand on. Side rest D on A. Carrier E. Holder F on carrier E. Weight G pivoted to main frame A at 4. Link H pivoted to weight G at 7 and to carrier E at 8.

In this example with the parts in the first position, Figure 4, the pivot 4, as in Figure 1, is above the main axis 2, but the link H is pivoted to weight G above the pivot 4 and to the carrier E above the main axis 2.

It will be recognized that it is not essential for the main frame A and carrier E to be pivoted about one and the same axis such as 2, but generally and for constructional purposes this may be preferable.

In the drawings gearing is shown for turning the main frame A about the axis 2, comprising a toothed segment 9 turnable with frame A and pinion 10 gearing with segment 9. Pinion 10 generally is power 75 driven. In Figure 4 pinion 10 is shown rotatable with toothed wheel 11 driven by a pinion 12. Wheel 11 and pinion 12 are omitted from Figures 5 and 6.

I claim:—

1. Tipping apparatus for wagons, comprising a platform for the wagon, a base for the platform to stand on, a main frame on which the platform is mounted to rock, a main axis about which the main frame is 85 mounted to turn, a carrier mounted to turn at or about the main axis, a side rest on the main frame for the outer side of the wagon, a holder on the carrier for the top of the wagon, a weight pivoted to the main frame 90 at a position above the main axis, a link pivoted to the weight and pivoted to the carrier, and means for turning the main frame about the main axis.

2. Tipping apparatus for wagons, comprising a platform for the wagon, a base for the platform to stand on, a main frame on which the platform is mounted to rock, a main axis about which the main frame is mounted to turn, a carrier mounted to turn 100 at or about the main axis, a side rest on the main frame for the outer side of the wagon, a holder on the carrier for the top of the wagon, a weight pivoted to the main frame, a link pivoted to the weight at a position above that of the pivot of the weight with the main frame and to the carrier at a position above the main axis, and means for turning the main frame about the main axis.

3. Tipping apparatus for wagons, comprising a platform for the wagon, a base for the platform, a main frame on which the platform is mounted to rock, a main axis 5 about which the main frame is mounted to turn, a carrier mounted to turn at or about the main axis, a side rest on the main frame for the outer side of the wagon, a holder on the carrier for the top of the wagon, a weight pivoted to the main frame, a link 10 pivoted to the weight and pivoted to the carrier, a toothed segment turnable with the main frame and a pinion gearing with the toothed segment.

15 4. Tipping apparatus for wagons, comprising a platform for the wagon, a base for

the platform, a main frame on which the platform is mounted to rock, a main axis about which the main frame is mounted to turn, a carrier mounted to turn at or about 20 the main axis, a side rest on the main frame for the outer side of the wagon, a holder on the carrier for the top of the wagon, a weight pivoted to the main frame, a link pivoted to the weight at a position above 25 that of the pivot of the weight with the main frame and to the carrier at a position above the main axis, a toothed segment turnable with the main frame and a pinion gearing with the toothed segment.

ANDREW WHELDON BILES.
